R. N. ROGERS.
 TYPE PLATE AND DRAWER FOR ADDRESSING MACHINES.
 APPLICATION FILED JUNE 4, 1907.
 Patented Dec. 8, 1908
 905,928.

Fig. 1

Inventor:
 Russell N. Rogers

by # UNITED STATES PATENT OFFICE.

RUSSELL N. ROGERS, OF CHICAGO, ILLINOIS, ASSIGNOR TO ROGERS ADDRESSER COMPANY, OF CHICAGO, ILLINOIS, A CORPORATION OF ILLINOIS.

TYPE-PLATE AND DRAWER FOR ADDRESSING-MACHINES.

No. 905,928.

Specification of Letters Patent.

Patented Dec. 8, 1908.

Application filed June 4, 1907. Serial No. 377,148.

To all whom it may concern:

Be it known that I, RUSSELL N. ROGERS, a citizen of the United States, and a resident of Chicago, Cook county, Illinois, have invented certain new and useful Improvements in Type-Plates and Drawers for Addressing-Machines, of which the following is a full, clear, and exact description, such as will enable others skilled in the art to which it appertains to make and use the same.

My invention relates to improvements in addressing machines and has particular reference to improvements in type-plates and plate drawers for such machines.

The object of my invention is to improve the form and construction of addressing machine type plates, and coincidentally, the form and construction of plate drawers.

My invention consists in a drawer having upright sides and suitable-ends, and preferably formed of sheet metal; to receive type-plates which have ears or lugs whereby they are suspended from the sides of said drawer.

My invention also consists in an improved type-plate, comprising a sheet of metal of requisite size, having lugs on its ends, said lugs being preferably in the form of depending arms or hooks, and said plate being provided with suitable ribs or flanges to hold it out of contact with a like plate when stacked therewith.

My invention also consists in various details of shape and construction and in combinations of parts; all as hereinafter described and particularly pointed out in the claims.

The invention will be more readily understood by reference to the accompanying drawings forming a part of this specification, and in which

Figure 1 is a side elevation of my novel drawer, containing a plurality of the novel type-plates referred to. Fig. 2 is a face view of one of said plates; Fig. 3 is a rear end elevation of the drawer, showing a plate therein; Fig. 4 is a lower edge view of the plate; Fig. 5 is a face view of a plate of modified construction; Fig. 6 is a lower edge view thereof; and Fig. 7 is the same as Fig. 6, but enlarged.

In the drawings A represents the drawer. This is preferably formed of a single sheet of metal and has straight upper edges, B, which are parallel with the bottom of the drawer. The drawer is of less height or

depth than the type-plates. Its ends are preferably closed by wooden blocks, C and D. The plates, when being placed in the drawer, by the operation of the addressing machine, fall into the forward end thereof and their lower edges frequently strike the drawer end, C. To protect this and to deaden the noise of the fall of the plates, I employ a lining, C', which is fastened to the end C, and the lower end, C'', of which extends back a short distance upon the bottom of the drawer.

The plates, P, shown in the drawer, are identical in construction, and a description of one will serve for all. Each plate, P, comprises a metal sheet, 1, to the back of which are attached parallel ribs, or flanges, 2, 2. These ribs, as best shown in Figs. 1, 2, and 4, may be formed by crimping or folding the plate upon intermediate lines 2'. After being shaped in this manner the plates are tinned and thus the cracks or seams at lines 2', are closed and the plate is made rigid. The upper edge 3, of the plate, is longer than the lower edge, 2, the latter being reduced by the formation of the hook-like ears or lugs, 4, on the ends of the plate. The openings, 5, in these ears fit the sides of the drawer, and the ears rest upon the upper edges thereof and support the plate in an inclined position, as shown in Figs. 1 and 3.

It will be obvious that when a plate is positioned in the drawer, with its lower edge resting on the bottom thereof, it cannot be twisted or displaced for the reason that the hooks or depending parts of the ears engage the outer sides of the drawer. No follower is required in my drawer for the reason that the plates are supported by the edges of the drawer; in other words, the plates are self-supporting as far as concerns their maintenance in upright, inclined positions in the drawer. The lower corners of the plate are rounded to more easily enter the drawer. The upper edge of the plate is provided with a turned over flange 6, which co-operates with a struck-up lug, 7, to hold the name card, 8, the latter being thus presented at the upper edge of the plate where it may be readily seen when the plates are sorted in the drawer. Upon most of my plates I employ either rubber or metallic sheets 9, bearing the type, 10. These sheets, 9, are glued or otherwise fastened to the face of the plate and extend transversely.

thereof. In lieu of the sheets, 9, I sometimes use a plurality of small sheet metal channels, 11, arranged side by side on the plate, and soldered or otherwise secured thereto. These channels readily receive rubber block type, 12, as shown in Figs. 5, 6 and 7.

As various modifications of my invention will readily suggest themselves to one skilled in the art, I do not confine the same to the specific structures herein shown.

Having thus described my invention, I claim as new and desire to secure by Letters Patent:

1. An improved type plate for addressing machines comprising a body or type carrying portion, having upon, and projecting from, its ends, depending hooks, shaped to engage the upper edges and the outer faces of the sides of a type drawer, substantially as described.

2. An improved type plate for addressing machines comprising a substantially rectangular body portion or plate proper bearing type on one side and hooked ears upon the ends of said body portion at the upper edge thereof and substantially parallel with

the ends of the plate, substantially as described.

3. An improved type plate for addressing machines comprising a substantially rectangular plate portion crimped upon lines parallel with its ends and thus provided with integral ribs, said plate bearing type on its non-ribbed side and at its upper corners provided with depending hook like ears, substantially as described.

4. An improved type-plate having ribs on its back, hook-like ears on its ends and a plurality of parallel channels on its face, substantially as described.

5. An improved type-plate having ribs on its back and provided with hook-like ears on its ends, said plate bearing type and a name card on its face, substantially as described.

In testimony whereof, I have hereunto set my hand, this 25th day of May, 1907, in the presence of two subscribing witnesses.

RUSSELL N. ROGERS.

Witnesses:

M. SIMON,
G. W. NELSON.
